UNITED STATES PATENT OFFICE.

WILLIAM A. TROUT AND CHARLES R. BUTLER, OF LONG BEACH, CALIFORNIA, AS
SIGNORS OF ONE-THIRD TO CHESTER A. RASMUSSEN, OF LONG BEACH, CALI-
FORNIA.

CASING HEAD.

Application filed April 11, 1922. Serial No. 551,486.

To all whom it may concern:

Be it known that we, WILLIAM A. TROUT and CHARLES R. BUTLER, citizens of the United States, residing at Long Beach, in the county of Los Angeles and State of California, have jointly invented new and useful Improvements in Casing Heads, of which the following is a specification.

This invention relates to casing heads, and has for one of its objects the provision of a device of this character which will positively prevent gas blow-outs. Another object is the provision of a casing head so constructed and formed that its removal from tubing is unnecessary when it is desired to pass tools such as fishing tools through the tubing. Another object is the provision of a casing head which does not depend upon the weight of the tubing for holding the various parts of said casing head in position.

In practicing the invention, we provide a casing head which may be formed in two parts, namely, a body portion and a cap portion. The body portion is provided with a tapered bore for a portion thereof and a uniform bore, the uniform bore being of an internal diameter equal to the internal diameter of the casing joined therewith. The tapered bore is adapted to receive slip members. The body is provided with a flanged portion and the cap member is likewise flanged and provided with a central bore. The flanged portion of the body carries a series of annular gaskets and said flange of the body and of the cap are provided with a series of perforations adapted to be aligned for the reception of bolts. The lower end of the body is screw-threaded exteriorly for reception of the collar member and the casing is likewise threaded exteriorly, whereby the collar may cooperate, not only with the threaded portion of the body but with the threads of the casing for holding the casing to the body. The bore in the cap member is threaded for a portion and the well tube passes up through the casing and the body member and is screw-threaded to the threaded portion in the cap. Likewise the slips are provided with teeth adapted to engage the sides of the tubing for aid in maintaining the tubing in position within the body. A collar member is carried by the cap member and said collar member unites a further tubing member to

the cap member, the said tubing member passing to a tank or pump. Openings are provided in the body portion for reception of pipes, which pipes allow communication with the interior of the casing, and whereby the pipes may conduct gas therefrom. Nuts are screw-threaded upon the bolts which connect the flanges of the cap and the body, and it will thus be seen that any gas pressure within the casing must be conducted through the gas tubes and cannot escape as between the body and the flange, owing to the rigid connection between the same and the gaskets. A notable difference between the present casing head and the conventional casing heads now on the market, resides in one particular, in that the packing is absolutely independent of the tubing wall. Most casing heads have the packing wedged in between the body of the casing head and the tubing, and the weight of the tubing holds the packing in place. If the gas pressure becomes excessive it will lift the tubing upwardly, and the gas will then escape around the packing, and as the gas usually carries sand with it, the sand rapidly cuts away the packing with the result that either an explosion or a disastrous fire almost always occurs. Furthermore, the present casing heads are so constructed that the head must be removed in order to fish for lost tubing through the casing. With our casing head it is only necessary to remove the tubing and the cap member and fishing tools may be inserted through the body of the casing head, as the inner diameter of the casing head is equal to the inner diameter of the casing. Another advantage of our casing head over the present form of casing head, resides in the fact that if the tubing becomes sanded up or stuck, the tubing may be easily lowered or jarred by simply removing the cap member and lifting the slips slightly to allow the tubing to slide. This usually overcomes the difficulty. With casing-heads as at present constructed it is impossible to work the tubing downward. If the casing head is removed in its entirety, often if the well is sanded or stuck, a pull upward on the tubing will cause the same to part, and a bad fishing job results. With the above and other objects in view, the invention consists in the novel and useful provision, construction, formation and inter-relation of the various parts, members

and features, as shown in the drawing, described in the following statement, and finally pointed out in claims.

In the drawing:

5 Figure 1 is a fragmentary cross sectional view of a casing head constructed in accordance with the invention;

10 Figure 2 is a cross sectional view taken on the line 2—2 of Figure 1, and looking in the direction of the appended arrows; and

15 Figure 3 is a plan view of said casing head.

Corresponding parts in all the figures are designated by the same reference characters.

15 Referring specifically to the drawing, the improved casing head is designated in its entirety and in one embodiment by A, and of which *a* is the body and *b* the cap member. The body *a* is provided at one end 20 with a flange 1 which is provided with a plurality of concentric grooves 2 adapted to receive gaskets or washers 3, which gaskets or washers project beyond the face of the flange 1, as shown at 4. The said body 25 *a* is annular; that is to say, is provided with a bore 5, a portion of which adjacent the flange 1, is tapered, as shown at 6, while a second portion as shown at 7 is uniform in diameter. The end as 8 of said body *a* is 30 provided with taper threads 9 adapted to have screw-threaded thereon an annular member or collar 10. The said collar likewise acts to maintain a casing 11 in cooperation with the casing head A, as by threading said casing 11 exteriorly as shown at 12 for engagement with the threads of the collar 10. The inner diameter or the annular gap of said casing is equal or nearly so to the annular gap of the bore portion 5 in 35 the body *a*. Obviously, the tapered bore 6 is of greater diameter than the annular gap in the casing adjacent the mouth thereof. The cap member *b* is annular in formation, which is to say, it is provided with a bore 40 13 which is tapered as at 14 and 15 adjacent the mouth portions. The surrounding walls of the tapered portions 14 and 15 are screw-threaded. The cap *b* is provided with a flange 16 and the said flange 16 is formed 45 with a plurality of spaced perforations or transverse openings 17. The flanged portion 1 of the body *a* is provided with correspondingly spaced perforations 18, and when said perforations 17 and 18 are in 50 alignment bolt members 20 may be passed therethrough, with nuts 21 carried on the threaded portions of said bolt members, whereby the members *a* and *b* may be securely clamped together. A portion as 21 55 of said cap *b* is provided with a tapered screw thread adapted to carry a correspondingly internally threaded collar 22. One portion of said collar receives the screw-threaded extremity of a tube 23.

60 In actual assembly, the well tube *c* passes

upwardly through the casing 11 within the body *a* and has its upper end as 24 in screw-threaded engagement with the tapered wall 15 of the cap *b*. This connection may be readily effected by rotating the cap when the 70 bolts 17 are not within the perforations in the flanges of the members *a* and *b*. Segmental slip members *d* provided with the usual teeth 25 are carried in the tapered bore of the body *a*, and said slips bite 75 against the periphery of the tubing *c*, as shown in Figure 1. It will thus be seen that after the slips have been positioned, and the tubing securely held within the body *a*, the cap *b* may be screw-threaded upon the 80 end 24 and the perforations in the flanges of the members *a* and *b* aligned, the bolts 17 passed therethrough, and the nuts 21 carried on said bolts tightened. This tightening action will of course wedge the face 26 85 of the flange 16 against the gaskets 3 carried by the body *a*. The body *a* likewise is provided with tapered openings 27 communicating with the annular space in said body, and tubes or pipes 28 are screw-threaded to the 90 walls surrounding said tapered bores, whereby any gas within the casing may be conducted through said pipes 28 either to a meter for registering the amount of gas pressure or to a gas tank for storage or both. 95

It is practically impossible for excessive gas pressure, which often reaches several hundred pounds per square inch, to lift the tubing *c* from its position, nor for the gas to escape over or through the gaskets 3. 100 As pointed out in the first part of this specification it is ordinary practice to place the packing about the tubing and the weight of the tubing within the casing head maintains the packing in position. If, then, the gas pressure within the casing is sufficient, that is, sufficient to lift the tubing, the packing, of course, will allow the gas to escape and it often happens that the tubing is 105 lifted entirely from the well hole. Even if this does not happen, and the tubing is simply lifted a small distance, this will allow the gas to escape about the gaskets at such a rapid rate that the sand carried by the gas will cut the packing away and the high velocity of the flowing gas will start a fire. All of this is overcome by our casing head, as the gaskets are independent of the tubing, and do not depend upon the 110 weight of the tubing for holding the same in place. Furthermore, the tubing if it becomes sanded up or stuck, may be easily dropped by removing the cap *b* from the body *a* and lifting the slip members *d* 115 slightly. It will thus be seen that we have provided a structure which is novel and which overcomes many of the difficulties now so prevalent on oil fields. 120

It is obvious that many changes, modifications and variations may be made in 125 130

practicing the invention, in departure from the specific description of the device, all of which modifications, however, may be made within a fair interpretation of the invention 5 as defined by the appended claims.

Having thus disclosed our invention, we claim and desire to secure by Letters Patent:

1. A casing head including a vented body member having an interior bore merging 10 into a conical bore opening at the upper end of the body, an offset flange carried by the body, and a tubing string suspension cap member having an interior bore adapted 15 for threaded engagement with the well tubing string, and said cap member also including a flange coextensive with and engaging the flange on the body, fastenings piercing the flange of the cap and the 20 flange of the body to prevent separation under gas pressure, and means for connecting piping to the cap member at the upper end of the bore.
2. A casing head including a vented body member having an interior bore, an offset flange formed at the upper edge of the body, a cap member including a body having a central bore, means for rigidly con- 25

necting a string of well tubing to the cap member at the lower end of the bore 30 whereby the tubing is held against longitudinal movement with reference to the cap, and a flange formed on said cap for covering the open end of the body and said flange being coextensive with the flange on 35 the body, and fastenings engaging said flanges and connecting the same to prevent separation of the cap and body.

3. A casing head including a vented body having an interior bore merging into a conical bore, a flange formed at the upper end of the body and provided on its upper face with a groove for receiving packing, a cap member including a body having a central bore internally threaded at its lower end 40 thereby to receive and suspend a string of tubing, said cap body having a horizontal flange portion covering the open end of the body member and resting on the packing carried by the flange thereof, and fastening means engaging the cap member and said body member for securing the same together. 45

In testimony whereof, we have signed our names to this specification.

WILLIAM A. TROUT.
CHAS. R. BUTLER.
